An ornamental design for a cigarette mini-pack shell and slide, as shown and described.

DESCRIPTION

FIG. 1 is a perspective view of a cigarette mini-pack shell and slide with beveled edges, showing our new design;

FIG. 2 is a front elevational view of a cigarette package comprising a pair of the mini-packs shown in FIG. 1 before being overwrapped, the rear elevational view being identical;

FIG. 3 is a right side elevational view thereof, the left side elevational view being identical;

FIG. 4 is a top plan view thereof, the bottom plan view being identical;

FIG. 5 is a perspective view of the cigarette mini-pack of FIG. 1 in a partially open position;

FIG. 6 is a perspective view of the cigarette mini-pack of FIG. 1 in a completely open position;

FIG. 7 is a perspective view of a cigarette package comprising a pair of the mini-packs of FIG. 1 with overwrap and a tear strip;

FIG. 8 is a perspective view of an alternate embodiment of a cigarette mini-pack shell and slide with rounded edges, showing our new design;

FIG. 9 is a front elevational view of a cigarette package comprising a pair of the mini-packs shown in FIG. 8 before being overwrapped, the rear elevational view being identical;

FIG. 10 is a right side elevational view thereof, the left side elevational view being identical;

FIG. 11 is a top plan view thereof, the bottom plan view being identical; and,

FIG. 12 is a perspective view of a cigarette package comprising a pair of the mini-packs shown in FIG. 8 with overwrap and a tear strip.

The appearances of the second embodiment of the cigarette mini-pack shell and slide in a partially open and completely open position are identical to FIGS. 5 and 6 respectively with the exception of the outer corners being rounded.
